UNITED STATES PATENT OFFICE.

GEORGE SCHWEMLEIN, OF CINCINNATI, OHIO, ASSIGNOR OF ONE-HALF TO
EDWARD C. MILLS, OF SAME PLACE.

ATTACHMENT FOR PAPER-RULING MACHINES.

SPECIFICATION forming part of Letters Patent No. 394,941, dated December 18, 1888.

Application filed March 31, 1888. Serial No. 269,088. (No model.)

To all whom it may concern:

Be it known that I, GEORGE SCHWEMLEIN, a citizen of the United States, and a resident of Cincinnati, in the county of Hamilton and 5 State of Ohio, have invented certain new and useful Improvements in Attachments for Paper-Ruling Machines, of which the following is a specification.

This invention relates to paper-ruling machines, and particularly to the ink-fountain and pens for head-line ruling.

It consists of an attachment which may be readily applied to any of the well-known ruling-machines now in common use.

15 The invention will be first fully described in connection with the accompanying drawings, and then particularly referred to and pointed out in the claims.

Referring to the drawings, in which like 20 parts are indicated by similar reference-letters wherever they occur throughout the various views, Figure 1 is a plan view of a paper-ruling machine provided with my improvements, the parts being shown in working position. Fig. 2 is a view taken through line x x , Fig. 1; but in this view the parts are upon an enlarged scale and thrown out of action. Fig. 3 is a side elevation of my attachment upon the same scale as Fig. 2, but 25 with the pens thrown into action, as in Fig. 1. Fig. 4 is an inverted plan view, upon an enlarged scale, of my improved pen-holder.

The ruling-machine, the side-framing timbers of which are indicated by the letter A, is 30 one of the ordinary kind now in common use, and need not therefore be specifically described. My ruling attachments are mounted upon this frame, as they may be upon any of the well-known machines of this class. The 35 description will be confined to the attachment, its construction, and mode of operation.

Upon each of the side beams, A, is secured 40 a plate, B, which has upwardly-projecting perforated lugs, b, which furnish bearings for the pivoted links C, which are journaled in these lugs b upon screws b', which pass through the lugs and are tapped into the cross-bars of the links C. The opposite ends of the links C are hinged to another link or chair, D, by 45 journal pins or screws d. The distances from center to center of the opposite pivot-pins

b' are slightly greater than the distances from center to center of the pins d, which pivot the chairs D in the opposite ends of the links C. By this arrangement of the centers 55 the chair D assumes opposite angles to the base B, so that when the attachment is thrown back in the working position, as shown in Figs. 1 and 3, the pens are brought down upon the paper traveling over the apron E, and 60 when thrown forward the pens are elevated considerably above the apron.

The chairs D have upwardly-projecting lugs d' upon each side, near the rear ends, between which are hinged the leaves F F' by 65 pivot bolts or screws d''. Each of these leaves has slotted bosses or boxes d''' on top to receive the ends of the pen-bar G, which is held in place by set-screws g, passing through the tops of the bosses d''' and pressing upon the 70 bar G. The pen-bar G, which carries the pen-holders H and fountains I I, is preferably made of a flat iron bar, the ends of which are twisted so as to bring them at a right angle to the center portion, in order that they may 75 enter the bosses d''', while the center portion is vertical to support the fountains I I, one of which is secured upon each side of the bar by soldering or other approved means.

My pen-holder is composed, preferably, of 80 the two parts H H', rigidly secured together. The part H has a downwardly-extending flange, h, at the rear, and the part H' an upwardly-projecting flange at its rear end. The inner lower edge of the flange h is rabbeted 85 to provide a groove to receive the upper edge of the pen-bar G. The pen-holders are secured in any desired position along the bar G by the set-screws h', which are tapped through bosses on the flange h. I find it more 90 convenient to make the pen-holder in two parts, as thus it is easier to give it a good finish than it would be if made in one piece, especially as I prefer to make the holders of hard rubber, which is non-corrodible by the 95 inks used for ruling. The ruling-pens h'' are held in place by the jaws h''', between which and the parts H H' they are clamped by screws which pass through the pieces h''', and are tapped into the pieces H H'. The 100 piece H' of the holder is notched in from one edge to as near the opposite edge as it would

be safe to do without weakening the holder too much. This notch is to permit the flannel to be drawn up from the fountain and over the top of the pens.

5 The leaf F upon the side of the machine at which the attendant stands is provided at its forward end with a ring, f, and the forward end is slotted to receive an eccentric, f', which is pivoted upon a pin passing from the edge 10 of the leaf through the eccentric f' and across the slot. The purpose of this arrangement is to temporarily throw the pens out of action when desired, which is done by taking hold of the ring f, slightly elevating the leaves F F', and 15 with them the pen-bar, when the eccentric, which is loosely journaled, will swing around by gravity until that portion of its periphery farthest from the journal will be underneath and resting upon the chair D when the ring 20 is released, holding the pens above the apron. The same end would of course be attained by securing the eccentric upon its shaft, extending the ends of the shaft out beyond the leaf and providing it with a thumb-knurl by 25 which the eccentric could be turned.

The pressure of the pens upon the paper is regulated by the set-screws k, which are tapped through the plates B. The same result would of course be accomplished by tapping the screws through the forward ends of 30 the leaves F F' when the device is constructed with these hinged leaves, as shown; but it is evident that these hinged leaves may be dispensed with and the pen-bar be secured directly to the chair D.

In head-line ruling it is desirable, if accurate work is to be done, that the head-line and faint-line pens be near together when the machine is running. Their proximity renders 40 it difficult and very inconvenient to properly adjust and regulate the pens and siphoning-flannels. This inconvenience my invention completely overcomes, as when the pen-beam and its attachments are thrown forward, as 45 shown in Fig. 2, ample space is provided between the pen-beams to accurately set and regulate the pens and work without liability of soiling the hands. A great saving of time is thus effected and better work insured.

50 Providing a means whereby the head-line pen-beam may be adjusted near to the faint-line pen-beam when the machine is set for work and readily carried away from the stationary pen-beam to accurately and conveniently adjust the parts in working condition, 55 I regard as a very valuable feature in a ruling-machine, and as this is, broadly considered, my invention I therefore do not limit

myself strictly to the construction herein set forth, but reserve my right to vary the same. 60 I have shown the best form known to me for attaining the benefits of my invention.

It will of course occur to the mechanic skilled in this branch of the art from a careful consideration of what I have here disclosed that the same result may be accomplished by known equivalent means, involving only such changes as his knowledge of mechanics would suggest without invention. Such mechanical changes I regard within the 70 spirit and scope of my invention.

What I claim as new, and desire to secure by Letters Patent, is—

1. In a paper-ruling machine, the combination, with the fixed pen-beam, of a movable 75 pen-beam supported by pivoted links, as described, whereby the two beams may be brought in proximity when the machine is in the working position and separated for convenience in regulating and setting the parts. 80

2. A head-line attachment for ruling-machines, consisting of the base-plates B, having lugs b, the links C, pivoted in said lugs, the pen-beam supports pivoted to the swinging ends of said links, and the pen-beam secured upon said supports, substantially as 85 hereinbefore set forth.

3. The combination, substantially as specified, of the lug-plates B, the swinging links C, the chairs D, pivoted to the swinging ends of 90 said links, the leaves F F', hinged to the rear ends of said chairs and the pen-beam G, pen-holders adjustable along said beam, and the ink-fountains secured to said beam.

4. In a paper-ruling machine, the combination of the hinged leaves F F', arranged upon opposite sides of the traveling apron, the pen-beam G, supported upon said leaves, and the eccentric f', journaled in the leaf F. 95

5. The combination of the movable pen-beam supported by pivoted links, the pen-holders and ink-fountain mounted upon said beam, and the adjusting-screws k, for regulating the pressure of the pens upon the paper, substantially as shown and described. 100

6. The head-line pen-holder, substantially as hereinbefore set forth, consisting of the parts H H', arranged one above the other, as shown, and grooved at the rear to fit over the pen-beam, the said part H' being notched to receive the ink-siphon and both parts having pen-clamps. 105
